UNITED STATES PATENT OFFICE.

HERMANN DEUTSCH, OF BERLIN-LICHTERFELDE, GERMANY.

WRITING AND DRAWING DEVICE.

Application filed July 28, 1923. Serial No. 654,387.

To all whom it may concern:

Be it known that I, HERMANN DEUTSCH, residing at 11 Marienplatz, Berlin-Lichterfelde, Germany, have invented certain new and useful Improvements in Writing and Drawing Devices, of which the following is a specification.

Writing and drawing devices are known in which a diaphanous sheet of paper, fabric or the like is arranged above a dark-colored slightly adhesive, bottom layer consisting of beeswax, paraffin wax or the like, and in which the writing or drawing is produced by pressing the paper sheet or the like against the adhesive bottom layer along the parts or lines to be made conspicuous by means of a style, so that these parts adhere to the bottom surface and the writing or drawing is thus made to appear in the color of the bottom adhesive surface. To obliterate the writing or drawing in the known devices the impressed sheet of paper or the like is simply lifted bodily from the adhesive bottom surface.

25 This invention relates to a writing and drawing device in which the marks are produced in the same manner as in the aforesaid device, but in which it is not necessary to lift the sheet of paper or the like from the adhesive surface into which parts of the paper have been impressed by the style. By this means the durability of the device is increased and an improved construction is obtained.

35 In accordance with the invention an obliterating device in the form of a strip, string, wire or the like extends across the writing tablet and is located between the adhesive bottom surface and the sheet of paper and the like and is arranged so as to be movable relatively to the paper and so that when it is moved it separates the adhering parts of the paper from the adhesive surface and thus obliterates the marks, writing, drawing 40 or the like that were produced by the impression of the paper into the adhesive layer.

In a preferred form of the writing and drawing device according to the invention 50 the adhesive bottom surface or layer with its superimposed diaphanous paper sheet or the like is arranged in the form of a unit adapted to slide in a flat case similar to a camera plate holder whose front wall has an opening or window through which the tablet is visible. The tablet is arranged so

that it can be drawn out almost entirely from the case like the cover of a camera plate holder. Arranged in the interior of the case so as to extend parallel to its open edge, and in the neighbourhood of this edge, 60 is a strip or thread of any preferred material which passes between the paper sheet and the adhesive layer beneath it, so that when the writing and drawing tablet, consisting of the adhesive bottom surface with 65 a paper sheet or the like stretched thereupon, is drawn out of the case, the obliterating strip or thread, by moving relatively to the writing tablet, separates the adhering parts of the sheet from the adhesive layer 70 beneath it, thus causing the writing or drawing on the tablet to be obliterated. When the writing tablet is then pushed back into the case its surface, which is accessible through the window or opening in the front 75 wall of the case, is ready for renewed use.

The writing device according to the invention may comprise a transparent protective sheet of flexible material, such as a film of celluloid or cellulose acetate composition, superimposed upon the paper sheet or the like. The style by which the impressions are made is then applied to the protective sheet instead of the paper sheet and the wear and tear to which the paper sheet 80 is subjected is thus considerably lessened.

In this modification the writing tablet consists of the adhesive bottom surface and two superimposed sheets one of which is of paper and the other of transparent protecting material. The obliterating device is again arranged between the adhesive bottom surface and the paper sheet which is covered by the protecting sheet.

A writing and drawing device according 95 to the invention in the form of a flat case like a camera plate-holder may comprise a case with windows or openings in its two opposite walls between which tablets arranged to be written upon on both sides 100 are placed, or which embrace two writing tablets placed back to back in the case.

Another feature of the invention consists in mounting the writing tablet upon a metal plate so that the layers of the writing and drawing tablet always lie smoothly upon one another since the metal plate cannot become warped. The obliterating member interposed between the paper sheet and the adhesive bottom surface may be arranged 110 so that it can be drawn out of the flat case.

so as to enable the writing and drawing tablet or parts of the same to be readily replaced when they are worn out or destroyed.

The invention is shown in the drawing 5 in which—

Fig. 1 is a front view of a writing and drawing tablet partly drawn out of its windowed case, and

Fig. 2 is a longitudinal section of Fig. 10 1 on the line II—II and Fig. 2^a is a partial section similar to Fig. 2 on an enlarged scale.

Fig. 3 is a cross section of Fig. 1 on the line III—III,

Fig. 4 a front view of a writing device 15 with a tablet provided with two writing surfaces.

Fig. 5 a longitudinal section of Fig. 4 on the line V—V, and

Fig. 6 a rear view of the case of Fig. 4 with the tablet partly drawn out and its top portion broken away.

Figs. 7 and 8 are a front view and a longitudinal section on the line IX—IX respectively of a writing device consisting of 25 a case with two pockets and a writing tablet in each pocket.

Figs. 9 and 10 are a front view and a longitudinal section of another modification 30 in which the obliterating device may be moved up and down between the paper sheet and the surface beneath it.

Figs. 11, 12 and 13 are a front view, a longitudinal section on the line XII—XII, 35 and a cross section on the line XIII—XIII respectively of another modification.

Fig. 14 is a front view and

Fig. 15 a longitudinal section on the line XV—XV of a writing device with a 40 removable obliterating member and writing tablet.

Fig. 16 is a view of the parts of the device according to Fig. 14 when taken apart.

The writing and drawing device shown in 45 Figs. 1, 2, 2^a and 3 comprises a flat cardboard of metal case *a* whose edges are stiffened and held together by folded metal strips *b*, one edge being left open for the introduction of the writing tablet. This 50 tablet consists of a bottom plate *c* coated with beeswax, paraffin wax or the like and having a sheet of paper *d* stretched over it, the paper sheet being covered in turn by a sheet *e* of transparent celluloid, cellophane or the like. The bottom plate *c* is connected to the impressible sheets *d*, *e* at the top and bottom edges *f* and *g* respectively by means of thin metal strips folded over the edges as indicated in the drawing. When the 60 writing tablet *c*, *d*, *e* is pushed into the case the top surface of the protecting sheet *e* is accessible through the opening or window *h* in the front wall of the case *a* so that marks can be produced by impressing 65 the surfaces *e*, *d* against the adhesive bot-

tom surface by a style or the like. Near the top open edge *i* of the case *a* an obliterating member, in the form of a wire or thread *k*, is arranged which extends from the one lateral edge of the case to the other and is inserted as shown more clearly in Fig. 8 between the lower plate *c* and the superimposed sheet of paper *d*. Instead of a thread *k* a narrow strip of cardboard paper, metal or the like may be provided.

When marks have been made by a style or the like on the tablet in the case *a* these marks may be obliterated by simply drawing the writing tablet *c*, *d*, *e* out of the case as indicated in Fig. 1. The obliterating member or thread *k* then travels along the bottom adhesive surface and separates the adhering parts of the paper *d* from the adhesive surface, thus causing the visible marks on the tablet to disappear. The manner in which the obliterating member *k* operates to separate the paper sheet from the bottom plate *i* is illustrated in Fig. 2^a in which the parts are shown larger than their natural sizes.

The interior surface *l* of the back wall of the case *a*, which becomes visible when the writing tablet is drawn out, may advantageously be arranged for the recording of temporary or permanent notes, or for 95 printed impressions such as advertisements or the like.

The flat case *a*, in the shape of a camera plate-holder, could also be arranged to receive a picture post card or a picture of any kind beneath the writing tablet, *c*, *d*, *e*, which said card or picture could be arranged to be withdrawn from the case by itself.

The protective sheet *e*, instead of being 105 arranged to move with the tablet, could be fixed in the case so that the bottom plate *c* with the paper sheet *d* only is arranged to be drawn out of the case.

The modified device shown in Figs. 4—6 110 differs from that shown in Figs. 1—3 only in the case *a'* having windows or openings *h*, *h'* in both of its walls and in a writing tablet having a bottom plate *c'* coated on both sides with layers of paraffin wax or beeswax above each of which paper sheets *d'* and 115 a protective sheet *e'* is stretched. In a writing and drawing device of this kind two obliterating strips *k'* are provided at the two opposite sides of the bottom plate *c'*. The writing and drawing plate as shown in Figs. 4—6 has two impressible sides and when the tablet is drawn out of the plate *c'* marks made on both sides of the plate are obliterated simultaneously.

In the modification shown in Figs. 7 and 8 the case *a''* is similar to the case *a'* of Figs. 4—6 except that it has two pockets with two writing tablets arranged back to back in the said pockets so that each tablet 130

can be drawn out by itself. Each tablet is constructed in the same manner as that of Fig. 1 and above each bottom plate *c* of the two tablets there is provided a transverse 5 obliterating thread or strip *k*. A writing and drawing device of this kind is also adapted for use on both sides and the marks on each side can be obliterated separately. The case *a''* is preferably provided with a 10 middle partition *l'* whose two sides may be used for recording purposes or printed forms or the like as indicated.

It will appear from the drawings that, if desired, the marks on a part only of a writing 15 surface may be obliterated by drawing the tablet only partly instead of entirely out of the case. The unobliterated portion of the record is then retained when the tablet is pushed back into the case.

20 In the modification shown in Figs. 9 and 10 the writing tablet consisting as usual of the bottom plate *c* and the superimposed sheets *d*, *e* of paper and protective material, is immovably fixed in the case *a'* which is 25 provided with metal borders and has a window in its one side like the cases described above. In this type the obliterating strip *k*⁴, whose ends project at both sides of the case and are guided thereat in suitably 30 formed slots, can be shifted lengthwise in the case. When marks are to be made on the tablet the obliterating strip *k*⁴ is moved into the upper position shown in Fig. 9 and when the marks are to be obliterated the 35 strip *k*⁴ is shifted downward to separate the paper sheet from the adhesive surface and thus cause the marks to disappear.

The writing and drawing device shown in Figs. 11, 12 and 13 differs from the afore 40 described devices in that the writing tablet consists of a metal sheet *c'*, a comparatively thin card-board sheet *c*² placed on the metal sheet and coated with beeswax or paraffin wax or the like, a diaphanous sheet *d* of 45 paper or the like above the card-board, and finally a transparent protective sheet *e* of celluloid, cellon or any other preferred transparent resistive material. The three sheets *c*², *d*, *e* are connected with the metal 50 sheet *c* by the top and bottom edges *f* and *g* of the latter being folded back upon themselves as shown in Fig. 12. An obliterating member *k* in the form of a strip extending 55 from one lateral edge of the case *a* to the other and parallel to the upper transverse edge *i*, is arranged near said upper edge of the case. The obliterating member *k* is 60 placed between the adhesive layer on the bottom plate *c*² and the paper sheet *d* superimposed thereon. This writing device is used in the same way as the device according to Figs. 1-3. The metal plate *c* 65 may be made of tin, aluminum or any other suitable material, the only important point being that the writing tablet itself is car-

ried by a metal plate which is not liable to become warped and is adapted to resist heat so that the layers *c*², *d*, *e* will always lie smoothly upon one another so as to enable the tablet to be slid easily in the case.

70 Under certain conditions the card-board sheet *c* could be dispensed with and the adhesive coating spread directly upon the metal plate *c*².

The modification shown in Figs. 14, 15 75 and 16 differs from that of Figs. 11, 12 and 13 in that the metal obliterating strip *k*² is arranged to be drawn out of the casing *a*. When the strip *k*² is in position in the case as shown in Fig. 14 the two 80 ends of the strip lie in notches *m* in the metal border *d* of the case *a* so that the ends of the strip do not project laterally beyond the edges of the case *a*. The one end of the strip *k*² is bent so as to form 85 a loop-shaped handle *n* and this end at least is arranged to engage frictionally or clampingly in a notch *m* of the metal border *d* so that when the strip *k*² is in position in the case *a* as shown in Fig. 14, 90 it cannot slip out automatically. To enable the obliterating strip *k*² to be readily introduced between the adhesive layer *c*² and the paper sheet *d* when it is inserted in the case, the bottom plate of the writing 95 tablet, is provided with a notch *o*, while the superimposed paper sheet *d* and the protecting sheet *e* have no such notches. Hence the front end of the obliterating strip *k*² will always enter automatically into its 100 proper position beneath the paper sheet *d*. As shown in Fig. 16 the writing tablet consisting of the parts *c*¹, *c*², *d*, *e* can be completely drawn out of the case *a* after the obliterating strip *k*² has been removed. A 105 damaged tablet or injured layers thereof can thus be readily replaced. After a new or repaired tablet has been inserted in the case *a* the obliterating strip *k*² is also reinserted and the writing device is then 110 ready for renewed use.

I claim:—

1. The combination with a writing and drawing pad comprising a base coated on one face with a plastic substance and a 115 tissue sheet superposed on said coating, the base with its coating and the tissue sheet differing in color, said sheet being adapted upon impression to adhere to said plastic substance along the lines of impression, of a receptacle for said pad, the writing and drawing surfaces of said pad being visible when the latter is in said receptacle, and a strip interposed between said base and said 120 sheet and attached to opposite edges of said receptacle, said pad being reciprocable in said receptacle transversely to said strip.

2. The combination with a writing and drawing pad comprising a base coated on one face with a plastic substance and a 130

- 5 tissue sheet superposed on said coating, the base with its coating and the tissue sheet differing in color, said sheet being adapted upon impressure to adhere to said plastic substance along the lines of impressure, of a case for said pad, said case comprising a windowed four-edged wall and a second four-edged wall joined to the first at three edges thereof, the writing and drawing 10 surface of said pad being visible through the windowed wall of said case, and a strip interposed between said base and said sheet substantially parallel to the open edge of said case and attached to opposite sides of the latter as and for the purpose described.
- 15 3. The combination with a writing and drawing pad comprising a metal base coated on one face with a plastic substance and a tissue sheet superposed on said coating, the 20 base with its coating and the tissue sheet differing in color, said sheet being adapted upon impressure to adhere to said plastic substance along the lines of impressure, of a receptacle for said pad, the writing and 25 drawing surfaces of said pad being visible when the latter is in said receptacle, and a strip interposed between said base and said sheet and attached to opposite edges of said receptacle, said pad being reciprocable in 30 said receptacle transversely to said strip.
4. The combination with a writing and drawing pad comprising a metal base coated on one face with a plastic substance and a tissue sheet superposed on said coating, the 35 tissue sheet being held in position by back-turned opposite edges of said base plate, the base with its coating and the tissue sheet differing in color, said sheet being adapted upon impressure to adhere 40 to said plastic substance along the lines of impressure, of a receptacle for said pad, the writing and drawing surfaces of said pad being visible when the latter is in said receptacle, and a strip interposed between 45 said base and said sheet and attached to opposite edges of said receptacle, said pad being reciprocable in said receptacle transversely to said strip.
5. The combination with a writing and drawing pad comprising a metal base coated on one face with a plastic substance and a tissue sheet superposed on said coating, the base with its coating and the tissue sheet differing in color, said sheet being adapted 55 upon impressure to adhere to said plastic substance along the lines of impressure, of a case for said pad, said case comprising a windowed four-edged wall and a second four-edged wall joined to the first at three 60 edges thereof, the writing and drawing surface of said pad being visible through the windowed wall of said case, and a strip interposed between said base and said sheet substantially parallel to the open edge of said case and attached to opposite sides of

the latter as and for the purpose described.

6. A device of the kind described comprising a case consisting of a windowed four-edged wall and another four-edged wall joined to the first at three edges and 70 unfastened at the fourth edge so as to leave an opening thereat; a writing tablet extractable from the said case through the said opening; said writing tablet consisting of a base plate, a plastic coating on the plate and a diaphanous sheet adapted upon impressure of the said sheet against the said coating to adhere along the lines of impressure; and an obliterating member located between the plastic coating and the diaphanous sheet, 75 said obliterating member being fixed at two opposite joined edges of the case and extending parallel and adjacent to the unfastened edge.

7. A device of the kind described comprising a case consisting of a windowed four-edged wall and another four-edged wall joined to the first at three edges except at two opposite notched portions of two of the said three edges, the fourth edges of the 90 wall being unfastened to each other so as to leave an opening at the fourth edges; a writing tablet extractable from the said case through the said opening; said writing tablet consisting of a base plate with a 95 notched edge, a plastic coating on the plate and a diaphanous sheet adapted upon impressure of the said sheet against the said coating to adhere along the lines of impressure; and an obliterating member adapted 100 to be inserted in the said notches and between the plastic coating and the diaphanous sheet.

8. A device of the kind described comprising a case consisting of a windowed 105 four-edged wall and another four-edged wall joined to the first at three edges except at two opposite notched portions of two of the said three edges, the fourth edges of the wall being unfastened to each other so as to leave an opening at the fourth edges; a writing tablet extractable from the said case through the said opening; said writing tablet consisting of a base plate with a 110 notched edge, a plastic coating on the plate and a diaphanous sheet adapted upon impressure of the said sheet against the said coating to adhere along the lines of impressure; and an obliterating member adapted 115 to be inserted in the said notches and between the plastic coating and the diaphanous sheet, the obliterating member being adapted to engage with the said walls at 120 the edges of the said notches.

9. The combination with a writing and drawing pad comprising a base plate coated on both faces with a plastic substance and a tissue sheet superposed on said coating on each side of said plate, the plate with its coating and the tissue sheets differing in 125

color and being adapted upon impressure to adhere to said plastic substance along the lines of impressure, of a receptacle for said pad, the writing and drawing surfaces of said pad being visible when the latter is in said receptacle, and a strip interposed between said base and each of said sheets and attached to opposite edges of said receptacle, said pad being reciprocable in said receptacle transversely to said strips. ¹⁰
In testimony whereof I affix my signature in presence of two witnesses.

HERMANN DEUTSCH.
